CLAIM

The ornamental design for a cartridge for medical injector, as shown and described.

DESCRIPTION

FIG. 1 is a perspective view of a cartridge for medical injector showing our new design;

FIG. 2 is a perspective view of the cartridge for medical injector;

FIG. 3 is a top view of the cartridge for medical injector;
FIG. 4 is a front view of the cartridge for medical injector;
FIG. 5 is a rear view of the cartridge for medical injector;
FIG. 6 is a right side view of the cartridge for medical injector; and,

FIG. 7 is a left side view of the cartridge for medical injector. The broken lines showing in the Figures are included for the purpose of illustrating portions of the cartridge for medical injector that form no part of the claimed design.
